FORM FOR CONCRETE AND THE LIKE

Richard C. Yates, Binghamton, N. Y., assignor
to Binghamton Metal Forms, Inc., Binghamton,
N. Y., a corporation of New York

Application February 28, 1950, Serial No. 146,850

4 Claims. (Cl. 25—118)

1

This invention relates to apparatus adapted for use in building concrete and similar structures and more particularly to road rails and similar forms used in the building of roads, walks, curbs and the like.

One of the objects of the present invention is to provide a novel form of the above character which is sturdy and rugged and hence capable of withstanding the shocks and stresses to which such equipment is subjected during ordinary handling and usage.

Another object of the invention is to provide a novelly constructed road rail or form which is fabricated from the fewest possible number of parts which are so integrated and associated as to insure maximum strength and stability with a minimum of weight.

Still another object of the invention is to provide a form wherein stake pockets are novelly combined with the form body and metallically integrated therewith, as by welding, in such a manner as to strengthen and otherwise advantageously supplement the same.

A further object is to provide a novel form for road building and the like which is so constructed as to advantageously locate the center of gravity and broaden the effective base to thereby improve the balance thereof in standing position and thus make the handling thereof easier when the same is being brought to line and grade, while at the same time reducing the weight without sacrificing essential strength.

A still further object is to provide apparatus of the above character wherein the form body, stake pocket and stake cooperate in a novel and advantageous manner to insure more secure support for the form to prevent vertical or tilting movement thereof.

The above and further objects and novel features of the invention will more fully appear from the following detailed description when the same is read in connection with the accompanying drawings. It is to be expressly understood, however, that the drawings are for the purpose of illustration only and are not intended as a definition of the limits of the invention.

In the drawings wherein like reference characters refer to like parts throughout the several views,

Fig. 1 is an isometric view, partly in section and with parts broken away, of one type of road rail or form embodying the present invention;

Fig. 2 is a horizontal sectional view with parts broken away, the section being taken on line 2—2 of Fig. 3;

2

Fig. 3 is an end view, partly in section, of the form shown in Fig. 1, the section being taken substantially on line 3—3 of Fig. 2; and

Fig. 4 is a view similar to Fig. 3 showing a modified embodiment of the invention.

The invention as illustrated in Figs. 1 to 3 of the drawings, by way of example, is embodied in a single section of a road rail or form adapted for use in building roads, walks, curbs or the like of concrete or similar materials. In use, a series of these sections are set up end-to-end along a desired line and grade in a manner well understood in the art to confine and support the concrete, or other material, until it hardens and thereby forms the vertical edge or side wall of the structure. These forms are subjected to rough handling and other severe shocks and stresses during use and must accordingly be very sturdily constructed to avoid bending or twisting thereof. On the other hand, forms of this character should preferably be of sufficiently light weight and so constructed as to permit easy and accurate installation thereof by a minimum number of persons and in a minimum period of time. Lightness of weight also contributes to the ease with which the form may be supported by stakes in the event the same is not resting upon the ground or other support as is often the case when forms are originally installed. The novel construction of the present invention accomplishes all of these results.

In the embodiment shown, the form body 10 is channel-shaped in vertical transverse section and comprises a web 11 which normally assumes a vertical position during use. An upper horizontal flange 12 extends at right angles to the web and is provided with a turned-down edge 14 thereby forming what may be called a double flange 12, 14. Extending at right angles from the lower edge of web 11 is a flange 15, the outer edge 16 of which is turned upwardly to form a so-called double flange 15, 16. The upper flange 12 may be provided with spaced slots 17 for locating division plates (not shown) which may extend between spaced parallel forms and cooperate therewith in a manner which is well known in the art.

The present invention comprehends means novelly integrated and associated with form body 10 for simultaneously strengthening the same and affording means whereby the same may be easily and properly positioned and supported with reference to the desired line and grade of the edge or side of the structure being built, while at the same time minimizing the weight and number of component parts and advantageously locating the

3

center of gravity of the completed form. Said novel means comprises a stake pocket or strap 18 which is made by stamping out and bending to shape a single piece of sheet steel. The radius of the bend or bite 19 at the center of the sheet is such that the inner surface thereof will closely frictionally engage the surface of and preferably resiliently grip a cylindrical stake 23, the purpose and operation of which will be hereinafter more fully pointed out.

The opposite halves or side webs 20, 20 of the pocket member 18 diverge toward and engage web 11 between flanges 12 and 15, the vertical edges of said pocket webs being welded to or otherwise metallically integrated with body web 11. The sides 20, 20 have upwardly extending tabs 21 which are of such size as to have a sliding fit in and completely fill the channel formed by the web 11 and the double flange 12, 14. The edges of said tabs are securely attached to the inner surface of said channel, such as by welding or other metallic integration. That portion of the stake pocket adjacent bend 19 extends outwardly beyond the outer edge of flange 15 and downwardly a distance approximately equal to the height of the up-turned edge portion 16, the vertical edges of the downwardly extending portion or tab being welded to the outer face of flange 16 as indicated at 22. Thus, outside the lower double flange of the form body the lowermost edge of the stake pocket is in the same or approximately the same horizontal plane as the lower face of flange 15. In this manner the stake pockets serve as means for assisting in supporting the form in edgewise or standing position (as shown in the drawings) before the stakes are inserted and driven as is highly desirable during the lining-up and installation procedure.

By thus integrating the form body 10 with one or more stake pockets 18 by welding the latter to flange 16, web 11 and double flange 12, 14, and thereby forming a rigid unitary structure, the resistance of the form to bending or twisting is greatly enhanced. This important advantage of the present novel construction makes it possible to use lighter materials and hence produce lighter forms without sacrificing essential strength. This construction also makes it possible to use only a minimum number of parts and combine the same in such a manner that the form may be easily kept free of any accumulation of concrete or other foreign materials. It will be understood that welding along the edges of the stake pocket which contact the form body may be either continuous or intermittent.

The lower edge of stake pocket 18 is preferably inclined upwardly toward web 11 in order to make it easy to remove any concrete or other material which may fall into the lower double flange 15, 16 between the sides of the stake pocket. The upper edges of the sides of the stake pocket outside of upper flange 12, 14 are preferably inclined downwardly toward the bend 19, whereby any blows by a sledge which accidentally miss stake 23 will strike only a glancing blow against the stake pocket and thereby reduce the possibility of damage. It will be noted, however, that since the stake does not have to pass through any confined space, which might be insufficient to pass the battered upper end of a stake, the latter may be driven before the form is mounted thereon. By like token the form may be readily removed from the driven stakes independently of the condition of the upper ends of the latter, thus making it easier to heave the stakes out of the ground.

4

Similarly, if it is desirable to drive the stakes while the form is in position the stake will pass through the pocket with sufficient freedom so that the latter will not interfere with the driving operation.

The number of stake pockets installed on each section or form is, of course, optional. In one suitable embodiment two stake pockets are used on a form 10 feet long, said pockets being spaced 5 feet apart and equi-distant from opposite ends of the form. Any suitable means known to the art may be employed for aligning and connecting the adjacent ends of successive sections. One suitable known means for this purpose is illustrated at the ends of the structure shown in Fig. 1.

Means are provided for securing the form 10, 18 to stakes 23 to hold the form in proper position and to support the same above the ground 20 when necessary. As shown, said means comprise a flat wedge member 24 which slidably extends through oppositely disposed slots 25, 25 in walls 20, 20 of the stake pocket. The slots are so positioned in relation to the stake 23 that the wider portion of the tapered member 24 may be securely wedged between the stake and the opposite ends of the slots as best seen in Fig. 2. Inasmuch as stake pocket 18 is rigidly integrated with form body 10, and is held in firm engagement 30 with stake 23 throughout a substantial vertical distance when the wedge is driven home to the left (Fig. 2), all of the parts will constitute a rigid unit so there cannot be any relative angular or vertical movement of the parts. In order to 35 increase the friction between stake 23 and stake pocket 18 and accordingly to enhance the holding power of the stake, the latter may be made of hard steel containing approximately .45% carbon and the pocket of soft steel containing approximately 40 .15% carbon. The high coefficient of friction between the stake and pocket, the large area of contact therebetween and the wedging of the stake between the side walls 20, 20 adjacent bend 19 all contribute to providing a large holding force. For this reason a single stake will often 45 be sufficient to properly position and hold a form section.

The thickness of wedge 24 is preferably only slightly less than the width of slots 25, 25 to 50 thereby permit free sliding movement of the wedge. In order to prevent accidental removal and loss of the wedge, one end thereof, for example, the righthand end in Fig. 2, may be made wider or thicker than slot 25 and the opposite end 55 may be provided with a bead 26 which will prevent passage of the wedge through the slot. This bead may be formed with a punch applied under high pressure to the opposite side of the wedge member.

60 As illustrated in the drawings, the stake pockets 18 are welded to the body of the form 10 along vertical edges only, i. e., along the vertical edges of walls 20, 20; tabs 21, 21 and the bottom tabs which engage the upstanding flange 16. By thus 65 making all of the welds vertical, danger of warping the form body during the welding process is substantially eliminated. In some instances, however, it may be desirable to provide welds which extend horizontally between the upper edges of tabs 21, 21 and horizontal upper flange 12. In constructing the form the weld at 22 is 70 preferably made first with the side walls 20, 20 of the stake pocket in firm engagement with the upper edge of upstanding flange 16. Thus, in the completed form many initial stresses are trans-

ferred through the stake pocket to the bottom flange of the form body without stressing the welded joints which connect the stake pocket and the form body.

The modification illustrated in Fig. 4 is identical with the embodiment above described except that the upstanding edge or lip 16 is eliminated from the bottom flange and the bottom edge of the stake pocket 18' is extended inwardly and welded to the upper face of single flange 15. An opening 27 is provided by cutting away the corners of the stake pocket walls to permit easy removal of any concrete or foreign matter which may drop into the pocket and lodge upon flange 15.

Although only two modifications of the invention are illustrated in the accompanying drawing and described in detail in the foregoing specification, it is to be expressly understood that the invention is not limited thereto. Various minor changes may be made in the design and arrangement of parts illustrated, as well as in the materials suggested, without departing from the spirit and scope of the invention as the same will now be understood by those skilled in the art.

What is claimed is:

1. In a construction form, a channel-shaped body member comprising a vertical web having flanges on one side at the upper and lower edges thereof, said flanges having marginal portions at the free edges thereof turned downwardly and upwardly, respectively, into parallel relation with said web, and a stake pocket consisting of a single piece of sheet metal bent centrally to form a stake embracing bend therein and sides diverging in vertical planes toward said web, each said side having edge portions thereof in engagement with said web and both said flanges to form a rigid brace between the latter, the sole connection between said piece and body member consisting of metallic bonds between vertically extending edges of said piece and vertically extending surfaces of said member, and said stake pocket extending laterally from said web beyond the upturned marginal portion of said lower flange and having a downwardly projecting tab portion with vertical edges metallically bonded to the face of said upturned marginal portion remote from said web.

2. A construction form as defined in claim 1 wherein the sides of the stake pocket have tabs extending into the channel space between said web and the down-turned portion of the upper flange, said tabs having vertically extending edge portions metallically bonded to the vertically extending surface of said down-turned flange portion facing said web.

3. In a construction form, a channel shaped body member comprising a vertical web and horizontal flanges at the upper and lower edges of said web, the lower flange having the marginal portion at the free edge thereof turned upwardly, said up-turned marginal portion being substantially parallel with said web, a stake pocket consisting of a single piece of sheet metal bent intermediate its ends to form a stake embracing bend therein and sides diverging in vertical

planes toward said web, each said side having edge portions thereof in engagement with said web and both said flanges to form a rigid brace between the latter, the central portion of the stake pocket including the stake embracing bend extending laterally beyond said up-turned marginal portion and having a downwardly projecting tab portion terminating in approximately the same plane as the lower surface of the lower flange and having vertical edges adjacent the vertical surface of said up-turned portion remote from said web, and means for securing said stake pocket to said member consisting solely of welds connecting the vertical edges of said sides to said body member, including welds connecting the vertical edges of said downwardly extending tab to said up-turned marginal portion of the lower flange.

4. In a construction form, a channel shaped body member comprising a vertical web and horizontal flanges at the upper and lower edges of said web, the upper flange having a marginal portion at the free edge thereof turned downwardly and the lower flange having the marginal portion at the free edge thereof turned upwardly, said down-turned and up-turned marginal portions being substantially parallel with said web, a stake pocket consisting of a single piece of sheet metal bent intermediate its ends to form a stake embracing bend therein and sides diverging in vertical planes toward said web, each said side having edge portions thereof in engagement with said web and both said flanges to form a rigid brace between the latter, the central portion of the stake pocket including the stake embracing bend extending laterally beyond said up-turned marginal portion and having a downwardly projecting tab portion terminating in approximately the same plane as the lower surface of the lower flange and having vertical edges adjacent the vertical surface of said up-turned portion remote from said web and said sides of the stake pocket having upwardly extending tabs which extend into and have edge-wise engagement with the walls of the channel between said web and said down-turned marginal portion of the upper flange, and means for securing said stake pocket to said member consisting solely of welds connecting the vertical edges of said sides to said web, the vertical edges of said downwardly extending tab to said up-turned marginal portion of the lower flange and the vertical edges of said upwardly extending tabs to the down-turned marginal portion of said upper flange.
